ENGINEER'S VALVE.

1,111,439.

Specification of Letters Patent. Patented Sept. 22, 1914.

Application filed December 24, 1913. Serial No. 808,909.

To all whom it may concern:

Be it known that I, HERBERT W. CHENEY, a citizen of the United States, residing at Milwaukee, in the county of Milwaukee and 5 State of Wisconsin, have invented a certain new and useful Improvement in Engineers' Valves, of which the following is a specification.

This invention relates to improvements in 10 the construction of engineer's valves adapted primarily for use in controlling the air brakes of railroad cars.

An object of the invention is to provide an engineer's valve which is simple in construction, efficient in operation, and in 15 which the valve seats are at all times kept free from undesirable accumulations of dust and dirt.

Some of the novel features of the valve 20 herein disclosed are claimed broadly in co-pending application, Serial No. 711,385, filed June 22, 1912.

With the introduction of puppet and piston valve types of engineers' valves for air 25 brake service and the substitution thereof for the well known rotary and slide valve types heretofore used, it has been found difficult and almost impossible to keep the valve seats free from accumulation of dust 30 and dirt so that the valves will at all times properly seat. The usual suction strainers for preliminarily straining the air admitted to the valves, although removing the greater part of the dust entrained by the air, do not 35 sufficiently purify the air to prevent accumulation of dust on the valve seats.

In the device of the present invention a secondary strainer is inserted directly within the valve casing and adjacent the inlet 40 valve, thus insuring proper purification of the air before its passage through the valve. Beyond this provision the present invention consists in so forming the valve seat that this seat will automatically tend to clean 45 itself, thereby insuring proper seating of the valve.

A clear conception of an embodiment of the invention may be had by referring to the drawing accompanying and forming a 50 part of this specification, in which like reference characters designate the same parts in the various views.

Figure 1 is a transverse vertical section through an engineer's valve of the combined 55 piston and puppet valve type. Fig. 2 is a

vertical section through an engineer's valve of the combined piston and puppet valve type, the section being taken along the line II—II of Fig. 3, looking in the direction of the arrows. Fig. 3 is a transverse horizontal section through an engineer's valve of the combined piston and puppet type, the section being taken along the line III—III of Fig. 1, looking in the direction of the arrows.

The engineer's valve casing consists essentially of a casing base 3, an intermediate casing portion 2, and a casing cap 1, these three casing elements being united by means of bolts 4 passing through the casing elements and clamped in place by means of nuts 5. The casing cap 1 is provided with a central bore through which the valve operating stem 6 passes. The valve operating handle 7 co-acts with the upper free end of the stem 6 and is adapted to oscillate this stem in the usual manner for normal operation. The lower end of the operating stem 6 is provided with a projection which fits into a central recess in the intermediate casing portion 2, the stem 6 being forced upwardly by means of a helical spring 21 which co-acts at its lower end with a portion of the base 3, and with its upper end against the lower end of the stem 6. The intermediate portion of the valve stem 6 is provided with quick-pitch screw threads 8 which are housed within the casing cap 1.

The exhaust valve 15 is of the combined piston and puppet valve type and controls the exhaust port 28 leading from the casing cap 1. This valve 15 has an upwardly extending valve actuating stem which projects into the interior of the casing cap 1. The valve 15 is normally held against its seat by 90 means of the air pressure and of a helical spiral spring 20. The inlet valve 14 is of the combined piston and puppet valve type and controls the inlet of air from the air inlet chamber 18, which is adjacent the valve 14, to the interior of the casing cap 1. The valve 14 is formed with a seating bead 22 which is adapted to co-act with the valve seat 23 which is preferably formed of leather or similar material. The valve 14 is normally held against its seat by means of a helical spiral spring 19, and has an upwardly extending valve guide 24, which extends into the interior of the casing cap 1.

The quick-pitch screw threaded portion of 110

the valve stem 6 is provided with a vertical movable operating member or block 10 which is guided vertically and prevented from rotating relative to the casing 1 by means of a stationary guide stem 11. The upper end of the block 10 carries a suitable oil pan 9 for keeping the working parts properly lubricated. The projection 13 extends laterally from the block 10 and is adapted to engage the lower surface of a nut 25 which is fixed to the upper end of the stem of the valve 15, upon vertical movement of the block 10 beyond a certain position.

The air inlet passage 16 formed within the casing base 3 communicates with the air inlet chamber 18 through a suitable passage. The strainer 17 is inserted within this communicating passage and serves to prevent undesirable particles from passing into the valve chamber 18. The strainer 17 preferably consists of a cylindrical sieve or screen having its interior filled with suitable straining material such as hair. The port 26 passes through the casing base 3 and intermediate portion 2 and normally establishes communication between the interior of the casing cap 1 and the brake cylinder.

During normal operation of the device, the valve actuating handle 7 may be oscillated, thereby causing the valve stem 6 to oscillate and to move the block 10 vertically within the casing 1 by virtue of the quick-pitch screw threads 8. As indicated in the drawing, the block 10 is in substantially mid-position so that movement thereof in an upward vertical direction would eventually cause the projection 13 to engage the nut 25 on the stem of the valve 15 and to raise the valve 15 away from its valve seat. During such opening movement of the valve 15, the spring 20 is compressed and communication between the interior of the casing 1 and atmosphere, is established through the exhaust port 28. Movement of the block 10 in a downward vertical direction, from the position shown, eventually causes the lug 12 to come in contact with the upper end of the valve guide 24 and to move the valve 14 away from its seat 23, thereby establishing communication between the valve chamber 18 and the interior of the casing cap 1.

As the passage 16 is normally in communication with atmosphere through the usual suction strainer, and since these usual suction strainers are intended primarily to remove only large particles of dust and dirt which are entrained by the air, it is found in practice that considerable undesirable foreign matter enters the passage 16. Such admission of foreign matter to the valve chambers of the old rotary and slide valve types of engineer's valves was not especially objectionable, due to the self-cleaning action of these valves in sliding over their seats.

With the use of the piston and puppet valve types of valves, it has, however been found that these particles of foreign matter which are admitted to the valve chamber eventually accumulate upon the valve seats and prevent securing of air tight closures. In order to eliminate this undesirable condition, the supplementary strainer 17 is placed directly within the valve casing adjacent the valve and between the passage 16 and the valve chamber 18. This strainer 17 which may be readily made to remove the greater portion of the impurities entrained into the passage 16, and which increases the cost of the production of the valves but a very slight amount, is removably inserted in a cored passage connecting the passage 16 in the base 3 and the chamber 18 in the intermediate portion 2. The portion of the passage 16 adjacent the lower end of the strainer 17 is laterally broadened so as to permit entrance of the air to the strainer around the entire lower portion thereof. The strainer 17 may be readily removed by a separation of the base and intermediate portion 2 of the casing.

By forming the inlet valve 14 with a circumferential bead 22 which is adapted to co-act with the valve seat 23, the air passing the valve 14 will automatically tend to remove any foreign matter which may have accumulated on the seating edge of the bead 22 and will tend to wipe such foreign matter into the recess adjacent the bead. In this way the valve bead 22 will be automatically kept free from accumulation while accumulation of solids upon the valve seat 23 will be prevented by the gravity action upon particles tending to lodge thereon. It should also be noted that the provision of a strainer 17 for preventing the admission of dust to the valve 14, does not only protect this valve but protects the valve 15 together with other working parts, as well.

It should be understood that it is not desired to be limited to the exact details of construction shown and described, for obvious modifications will occur to a person skilled in the art.

It is claimed and desired to secure by Letters Patent:

1. In an engineer's valve, a casing, a piston valve within said casing, said valve comprising a valve member and a seat member, one of said members being formed with an upwardly directed beaded seating portion, means for operating said valve, and means within said casing for preliminarily purifying the air admitted to said valve.

2. In an engineer's valve, a casing, a valve within said casing, said valve comprising a valve member and a seat member, one of said members being formed for the prevention of accumulation of foreign matter thereon, means for operating said valve, and

a strainer within said casing and adapted to preliminarily purify air admitted to said valve.

3. In an engineer's valve, a casing, a piston valve within said casing, said valve being formed with an upwardly directed beaded seating portion, means for operating said valve, and means within said casing for preliminarily purifying the air admitted to said valve.

4. In an engineer's valve, a casing, a valve within said casing, said valve being formed for the prevention of accumulation of foreign matter thereon, means for operating said valve, and a strainer within said casing and adapted to preliminarily purify air admitted to said valve.

5. In an engineer's valve, a casing, a

plurality of puppet valves within said casing, means for operating said valves, and a strainer within said casing and adapted to preliminarily purify air admitted to said casing past one of said valves.

6. In an engineer's valve, a casing, a plurality of puppet valves within said casing, means for operating said valves, and a removable strainer within said casing and adapted to preliminarily purify air admitted to said casing past one of said valves.

In testimony whereof, the signature of the inventor is affixed hereto in the presence of two witnesses.

HERBERT W. CHENEY.
